AMOS B. CASSELMAN, OF WASHINGTON, DISTRICT OF COLUMBIA.

SUSPENSORY.

1,313,165.

Specification of Letters Patent.

Patented Aug. 12, 1919.

Application filed December 18, 1918. Serial No. 267,253.

To all whom it may concern:

Be it known that I, AMOS B. CASSELMAN, a citizen of the United States, residing at Washington, in the District of Columbia, 5 have invented certain new and useful Improvements in Suspensories; and I do hereby declare the following to be a full, clear, and exact description of the same, reference being had to the accompanying drawing, forming part of this specification.

Suspensories of the type to which the present invention relates are a necessary but unfortunately, as heretofore constructed, an inconvenient and uncomfortable adjunct 15 to the personal equipment of those obliged to employ them. The objects of the present invention are primarily to provide a suspensory which will, in a large measure, overcome or avoid many of the defects of 20 prior devices and reduce the discomfort of the wearer.

Generally speaking the invention contemplates the provision of a suspensory requiring but a single waist band or supporting member and a readily separable scrotum bag whereby the latter may be renewed, 25 laundered or interchanged with others of different size or form to suit personal wishes or proportions of the individual, means being provided whereby the bag may be readily adjusted for position and the privates of the person easily and quickly placed 30 within or removed from the same. Provision is also made whereby the bag is prevented from collapsing around the privates 35 due to the weight of the latter.

In the present embodiment, the objects sought are partly attained by an exceedingly simple supporting arrangement for 40 the scrotum bag, in which the use of straps extending underneath the pelvis and between the legs of the wearer is entirely eliminated, together with an arrangement for supporting the bag which permits of 45 the bag being adjusted vertically without the necessity of manipulating or removing the body encircling belt.

The novel features will be particularly pointed out and specified in the claims at 50 the end of the specification.

In the accompanying drawing there is shown a front view of a suspensory constructed in accordance with the present invention, illustrating the mode of application 55 to the body of the wearer.

As shown, the suspensory includes a body

encircling belt A usually made of webbing or flat tape and provided with a buckle A' whereby the belt may be adjusted about the body of the wearer. The buckle may 60 be of any preferred construction for adjustably securing the free end a. In the front, the belt A is preferably divided, as shown, and the opposite end portions B, B' will, when in position on the body, form 65 downwardly depending reaches which are made long enough to extend along the opposite sides of the lower abdominal region or groin of the wearer.

At is lower extremity, each reach B, B' 70 is provided with a ring C. Secured to the rings C, and bridging the space between them, is the member which supports the scrotum bag E. This supporting member, indicated at D, is preferably formed of a 75 strand of tape material so secured to the rings C as to form two depending reaches D', D², between said rings, from each of which one end of the scrotum bag E is supported or suspended. Preferably, the two 80 reaches are formed by permanently attaching one end of the tape to one ring C, as at d, then doubling the tape upon itself in the other ring to form a loop and then fastening the end of the tape to the first ring 85 C, as at d', this latter end being detachably secured or tied to the ring and the looped end of the tape being slidably held in the other ring so that the length of the reaches D', D², formed by the loop may be changed 90 to adjust the height of the scrotum bag, as will presently appear.

Secured to the opposite ends of the scrotum bag E, and adjacent the top thereof, are two suspension members preferably in 95 the form of loops F, one of which is carried by the reach D' of the supporting member D, and the other by the reach D². By attaching the suspension members F of the bag to the reaches of the supporting member in this manner, each reach of the latter is subjected to only one downwardly directed strain, the points of stress on the respective reaches being located off to the opposite sides of the vertical center of the 100 scrotum bag. As each reach is, therefore, pulled down at only one point, when the reaches have been drawn taut, as shown in the drawing, the suspension members or loops have no tendency to slip or move 105 toward each other but on the contrary they are held in spaced relation to each other.

and the upper portion of the bag held distended.

As before mentioned, the suspension members F of the bag are preferably in the form 5 of plain loops and are slidably carried on the reaches D', D² of the supporting member D so that they will easily slide when the tape is shortened or lengthened to adjust the bag vertically. Inasmuch as loops F are 10 loose on the reaches D', D², to adjust the scrotum bag vertically, it is only necessary to untie the end d' of the tape and take in a little of the tape if the bag is to be elevated or let out a little so that the reaches D', 15 D² will sag a little if the bag is to be lowered. Furthermore, the loops F being loose on the reaches D', D², the scrotum bag may be detached to permit a new one to be substituted or for any other purpose desired 20 such as laundrying, etc.

As the reaches D', D² extend down into the groin and follow closely the abdominal lines, the scrotum bag E will hang in line with and directly underneath the scrotum, 25 the latter itself assisting in holding the bag in place. This method of suspending the scrotum bag obviates the necessity for straps passing beneath the legs and around the back of the wearer, a common cause of 30 discomfort to the wearer of a suspensory. In addition, the position of the bag directly underneath the scrotum renders it possible to construct the bag sufficiently shallow to permit the penis being passed over the 35 upper edge of the bag, thus simplifying the bag construction by doing away with the usual uncomfortable penis opening.

The tape looped between the ends of the belt forms, in effect, two flexible supporting 40 members, a single tape doubled through the ring being employed rather than two separate tapes in order to simplify the construction and to provide for an evenning up of the load on the two members and the incidental supporting of the ends of the bag 45 at the same level.

What I claim is:

1. A suspensory comprising a body encircling belt having its ends separated, a 50 scrotum supporting bag, suspension members attached to the opposite ends of the upper portion of the bag, and adjustable supporting means extending between the ends of the belt and connecting the belt and 55 suspension members, said supporting means being slidably connected to one end of the belt and adapted to maintain the suspension members in spaced relation, whereby the top of the scrotum bag is held distended.
2. A suspensory comprising a divided 60 body encircling belt, a scrotum supporting bag, suspension members attached to the opposite ends of the upper portion of the bag, and supporting means extending between 65 the ends of the belt and connecting the belt

and suspension members, the supporting means being slidably connected to one end of the belt and adapted to maintain the suspension members in spaced relation, whereby the top of the scrotum bag is held distended, said suspension members being detachably secured to the supporting means. 70

3. A suspensory comprising a divided body encircling belt, a scrotum supporting bag, suspension members secured to the opposite ends of the top of the bag, and a pair of supporting members connecting the ends of the belt, there being a slidable connection between the supporting members and one end of the belt and each of said 80 supporting members having one of the suspension members of the bag secured thereon. 75

4. A suspensory comprising a divided body encircling belt, a scrotum supporting bag, suspension members secured to the opposite ends of the top of the bag, and a pair of adjustable supporting members, connecting the ends of the belt, there being a slid- 85 able connection between the supporting members and one end of the belt and each 90 of said supporting members having one of the suspension members slidably secured thereon.

5. A suspensory comprising a divided body encircling belt, a scrotum supporting bag, loops secured to the opposite ends of the top of the bag, and a pair of adjustable supporting members detachably secured to one end of the belt and slidably connected to the other end, each of said supporting members having one of the loops of the scrotum bag 95 slidably secured thereon. 100

6. A suspensory comprising a divided body encircling belt, a scrotum supporting bag, a pair of adjustable supporting members detachably secured to one end of the belt and slidably connected to the other end, and connections between the opposite ends of the upper portion of the scrotum bag and the 105 respective supporting members. 110

7. A suspensory comprising a divided body encircling belt, a scrotum bag, supporting means for said bag comprising a single member connecting the ends of the belts and formed into two relatively movable depending reaches, and suspension members secured to the opposite ends of the bag and the respective reaches of the supporting means. 115

8. A suspensory comprising a divided body encircling belt, a scrotum bag, supporting means for said bag comprising a single member extending between the ends of the belt and formed into two relatively movable depending reaches, said member being slidably secured to one end of the belt, and suspension members secured to the opposite ends of the bag and the respective reaches of the supporting means. 120 125

9. A suspensory comprising a divided 130

- body encircling belt, a scrotum bag, supporting means for said bag comprising a tape looped between the ends of the belt to form two relatively movable depending reaches, the looped end of the tape being slidably secured to the belt, and connections between the opposite ends of the bag and the respective reaches of said tape.
- 5 10. A suspensory comprising a body encircling belt having its ends separated, a scrotum supporting bag, suspension mem- bers attached to the opposite ends of the upper portion of the bag, and supporting means extending between the ends of the belt and connecting the belt and suspension 15 members, said supporting means being slidably connected to the belt and adapted to maintain the suspension members in spaced relation, whereby the top of the scrotum bag is held distended.

AMOS B. CASSELMAN.
